(57) **CLAIM**

The ornamental design for a headgear-to-frame connection component for respiratory mask, as shown and described.

DESCRIPTION

FIG. 1 is a perspective illustration of a first part of a headgear-to-frame connection component for respiratory mask according to our new ornamental design;

FIG. 2 is a perspective view of a second part of the headgear-to-frame connection component that engages with the part; FIG. 3 is a top view of the first part; and, FIG. 4 is a top view of the second part.

The broken lines in the drawing figures are included to show unclaimed portions only and form no part of the claimed design.
